PROCESS OF PREPARING MALT EXTRACT

Frederick L. G. Kunz, Lake Forest, Ill.

Application August 28, 1952, Serial No. 306,889

13 Claims. (Cl. 99—51)

My invention relates to an improvement in process of preparing an extract from malted, unmalted, or malted and unmalted cereal grain. One object is to increase the surface area of the material being treated and thereby provide a higher extract yield and a shorter reaction time, because of faster, more thorough wetting and dispersion of solids in the liquid reagent phase.

Another object of the invention is to provide better enzymatic action.

Another object is to provide an improved procedure for recovering the liquids. The fine grinding characteristic of my invention so reduces the size of the particle and so distributes the starch and the enzymes that they are held readily available for the necessary enzymatic action.

Another object of the invention is a procedure which involves a minimum unit labor cost.

Another object is to obtain the ultimate material yield in the brewery, distillery or allied or parallel processes, from malted or unmalted grains employed to yield a liquid extract.

Another object is to provide continuous centrifugal separation of insoluble solids from liquids and continuously and simultaneously discharge the separated insoluble solids and the clarified liquids.

Other objects will appear from time to time throughout the specification and claims.

This application is a continuation in part of my pending application Serial No. 242,204, filed August 17, 1951, now abandoned.

My invention is illustrated more or less diagrammatically in the accompanying drawings, wherein:

Figure 1 is a flow sheet or diagrammatic plant lay-out;

Figure 2 is a similar diagram illustrating a modification of the device disclosed in Figure 1.

Like parts are indicated by like characters throughout the specification and drawings.

I employ a prepared grain substantially finer than is conventional in current practice. Referring to Figure 1, prepared and differentiated grain solids are delivered to a mechanical disintegrator (not shown) for dispersion of solids in a liquid phase. This is necessary because with the finely ground solids that I propose to use it is essential that the solids be dispersed in the liquid with a minimum of delay as otherwise enzymatic action is irregular and continues with respect to various parts of the solids for different lengths of time and this results in unsatisfactory results. As a matter of fact, it is of the utmost importance that the entire mass of solids be dispersed in the liquid phase in from five to ten minutes' time. Thereafter this material is mashed in the mash tongue A in the usual manner except that the time of mashing may be shortened because of the initial complete dispersion of the solids. The mash from the mash tun A is delivered to an initial centrifuge B1 for the initial separation of insoluble solids from the clarified liquid extract. The solids pass from the centrifuge B1 to the dilution tank C. The liquid from the centrifuge B1 goes to a second stage centrifuge B2, in series with B1. The clarified liquid from the centrifuge B2 is suitable to be delivered to the kettle, but the sludge or recovered solids are returned to the sparge tank C, are suitably mixed with sparging water, and the sparged solids again pass to a series of centrifuges D1 and D2. The liquid from the centrifuge D1 is re-centrifuged in the centrifuge D2 and the clarified liquid from the centrifuge D2 is passed on

2

to the kettle with the liquid from the end centrifuge B2 of the earlier series. The extracted solids from the second series of centrifuges D1 and D2 may go to a dryer or to other suitable disposal.

As an example, I propose to use a slurry type of mash, quite thin because a thicker mash will not centrifuge. The mash will include between two and one-half and three and one-half parts by weight of water to one part by weight of dry solids (as its basis). The malt will be ground, husk and all so that sixty to ninety percent will pass through a one hundred mesh screen. The grind must be uniform but occur without heating of the product and the remaining ten to twenty percent, too coarse to pass through the screen will nevertheless as a result of the grinding, be small enough in size and of such volume that it also will not interfere with the centrifuging. Under some circumstances the remaining ten to twenty percent of oversized solids may be discarded or may be subject to further treatment such as reclassification and further re-grinding. The water and the solids enter the mash tun having been wetted for but a short time, for example, ten minutes, because if wetting takes too long, the enzymatic process will go too far with the earlier wetted elements of the mash.

The mash contents must, of course, be completely wetted and if by any chance the mechanical dispersion has not wetted all of the solids, and this will seldom if ever happen, at any rate the situation will be set up such that in the mash tongue wetting is immediately completed and enzymatic action can take place commencing at a predetermined initial temperature which, for example, may well be 100° F., the mash being held at this temperature for perhaps as much as a half hour, the mash slurry being continuously circulated. Thereafter, the mash will be heated to approximately 154° F., more or less, such temperature being held for twenty minutes, more or less, until conversion is completed depending on the amount of sugar desired. It is essential that nothing remains in the mash higher in molecular weight than maltodextrine.

Barley malt adjuncts, such as corn grits or rice will be ground to the same specification as the barley malt, will be mixed with water and rice to ten percent malt and cooked at a temperature finally reaching not over 212° F. The principal adjuncts with which I am dealing are corn grits or brewers rice or other raw grain; the adjuncts do not have any substantial amount of enzymes. The enzymes are in the malt. They are necessary to convert the starch in the grain to sugars, and to solubilize certain proteins.

Standard practice is to boil the grits or other adjuncts for about one-half hour. By grinding them very fine, I am able to reduce the total conversion time because the finer the grind the more rapid the enzymatic action can be as a result of the more intimate contact of the enzymes with the entire mash when the content of the cooker is dropped into the mash tun.

The less the boiling time, the better. This is because boiling dissolves coloring matter, gives a darker end product and is likely to result in undesirable taste. Fine grinding and short boiling time reduces these difficulties and, under some circumstances, fine grinding may make it possible to avoid boiling altogether.

After cooking, I drop the contents of the cooker at 212° F. or thereabout into the main mash tun, the temperature of which may be of the order of 100° F. The temperature in the tun immediately rises. The temperature of the material in the tun before the dropping in of the cooker contents may vary depending on the particular product desired. The temperature will normally be controlled to get the desired sugar production.

Finely ground material of the type which I propose to use cannot be used in connection with the usual type

of mash tun and filter, malt extract production because fine grinding will result in clogging the filter to the extent that the malt extract cannot be satisfactorily produced.

Referring now more specifically to the disclosure of Figure 2, 1 is a converter. It may discharge by gravity to the first centrifuge as shown in Figure 2 or the mash may be discharged by gravity to a pump and thereby supplied to a plurality of such centrifuges in parallel.

I propose to hold the mash in the tun until the desired conversion is completed, after which the mash will be centrifuged. Referring now to Figure 2, this mash will be made up of malt heated in the tun to a temperature as above indicated of the order of 100° F. The adjuncts will be cooked in the cooker 2 and then dropped into the tun and the adjuncts plus the malt will remain in the tun until conversion is complete. Then the contents of the mash tun is discharged to centrifuge 3. Centrifuge 3 separates fibrous material from the liquid and discharges it direct to a solids dilution tank 4. The effluent from the centrifuge 3 is supplied to centrifuge 5. The centrifuge 5 separates insoluble proteinaceous material which is returned to the solids dilution tank 4. The remaining extract or effluent from the centrifuge 5 is discharged to the kettle 6.

The solids and liquids from the solids dilution tank 4 are supplied to the centrifuge 7 which makes the same kind of separation as was accomplished by the centrifuge 3, discharging fibrous material to the solids dilution tank 8, while discharging the effluent to the centrifuge 9. The centrifuge 9 separates the insoluble proteinaceous material and discharges the extract or effluent to the kettle 6. The insoluble proteinaceous material will be discharged to be dried or otherwise treated without going to the second solids dilution tank 8.

The centrifuge 10 will receive the material from the dilution tank 8 and since the insoluble proteinaceous material from the centrifuge 9 bypasses the tank 8, the centrifuge 10 will treat only the fibrous material and the extract or effluent, the fibrous material being separately discharged, and the extract going from centrifuge 10 to the kettle.

There are circumstances when it is highly desirable to separate and have as separate products, on the one hand, fibrous material, on the other hand, proteinaceous material.

By this arrangement, the mash is subjected to a plurality of centrifuging steps, and the separated solids to a plurality of solids dilution steps, making the further centrifuging possible. The resultant fibrous solids are discharged from the system as practically fully extracted. The resultant proteinaceous material is discharged from the system as practically pure insoluble proteinaceous material for further use. The extract from the malted and unmalted cereal grains is discharged to the kettle.

In considering the details of my method and its position in the general brewing process, the following points may be noted: The husk of the barley malt may be separated from the other constituents and separately ground and processed, the water extract of the malt husks being later added to the main portion of materials being processed. Or, as an alternative, the entire barley malt may be ground as a whole and processed.

The continuously and centrifugally separated and discharged solids are water washed to remove the extractible components. The last wash water is immediately available and may be used as the initial water or as part of the water required for the new material for subsequent, successive mashes, brews or slurries, or it may go to the kettle 6, as shown in Fig. 2.

In my process I use a very finely divided or ground grain or malt. I do not wish to limit myself to any particular method of or mechanism for grinding or pulverizing my material, but I have found that a grinder which will reduce both the husk and the endosperm to uniform fineness in the order of eighty to ninety percent through a one hundred mesh screen is suitable.

My prime purpose is to obtain the ultimate material yield in the brewery, distillery or allied or parallel processes, from malted or unmalted grains, including but not limited to barley malt and corn grits. These are made to yield a liquid extract, brewer's wort or distiller's slurry, through the addition of water and conversion factors.

As will be clear from the drawing filed herewith, I am able to separate continuously the liquids and solids resulting from the mashing operation by the use of 10 centrifugal machines or centrifuges.

Among the advantages of my method are, initially, the use of a much more finely ground or divided malt or other grain stuff than can be used with a filter bed comprised of the materials treated. This is not possible 15 with the existing equipment now in use. I am able in a continuous process to separate insoluble solids from a liquid extract and I am able to separate liquids from solids without establishing a filter bed of the materials being treated. Prior art practice does not permit continuous separation.

The currently used brewery equipment does not permit or maintain a positively controlled, constant, uniform rate of flow of liquid.

It will be realized that whereas I illustrate a plurality 25 of primary centrifuges or centrifuging zones and secondary centrifuges or centrifuging zones, it will be understood that, under some circumstances, I may employ a single primary centrifuging zone and a single secondary centrifuging zone.

It is to be emphasized that previous methods give a 30 mixture of the total insoluble solids, primarily protein and fiber. My method separates the protein from the fiber, discharging each of them separately from the system.

The relationship between the centrifuges is of the utmost importance. Two separate types of centrifuge are 35 used in pairs. The first centrifuge in each pair extracts and discharges primarily fibrous material and that fibrous material after passing through the dilution tank and being mixed with other elements is treated by the first 40 centrifuge of the next pair and so on. The second centrifuge of each pair separates the insoluble proteinaceous material from the syrup or extract, discharging the extract to the kettle and returning the insoluble proteinaceous portion to the dilution tank where it is mixed with 45 the fibrous material discharged by the first centrifuge, the mixture being again treated for the same kind of separation. Thus at the end of the series, I am able to get substantially pure fibrous material and substantially pure proteinaceous material, each as a separate product, the remaining liquid or extract being supplied to the 50 kettle.

Only solubles are wanted in the kettle. The insolubles must be substantially removed from the liquid before 55 it enters the kettle. The insolubles are of two principal kinds—fibrous and proteinaceous. It is usual in this art to separate the solubles and the insolubles and when the insolubles are mixed fibrous and protein, their use is limited. I propose to separate the fibrous insolubles or 60 solids, the proteinaceous insolubles, and the solubles because there are many important uses for separated fibrous insolubles on the one hand and proteinaceous insolubles on the other.

The mixture of fibrous insolubles and proteinaceous insolubles is much more difficult to dry than are the 65 separated insolubles.

By using a thin slurry in the mixing tank between successive centrifuging operations, I am able to use a very much smaller amount of water and get a larger amount 70 of extract because the solids are dispersed through the liquid phase and there is no necessity of running large volumes of water through a mass of solids subject to channelling as in the prior practice.

The initial mix in the mash tun is preferably from 75 two and one-half to three parts by weight of water to

one part solids (as is). The fibrous material returned from the centrifuges to the mixing tank is substantially hand dry. Therefore water must be added in about the same proportion, two and one-half to three parts of water to one part insolubles, but because the volume of solid material discharged from the two centrifuges to the dilution tank is much smaller than that originally present in the mash (due to previous extraction), a lesser amount of water is necessary.

From a given amount of material in the mash tun, I am able to get a larger amount of extract or, if desired, the same amount of extract of higher specific gravity than has heretofore been possible. In other words—for example—from ten percent less material in the mash tun I am able to get the same quantity of extract at the same specific gravity for the kettle. The fiber discharged by the first centrifuge goes to the dilution tank as a substantially dry product and is there washed, and then is treated again in the next centrifuge so that if there is any soluble proteinaceous material or any other solubles left with the fibrous solids after the first treatment, those solubles will be extracted in the second or third treatment.

The husk or fibrous material is basic when filtering is relied upon because the husk makes the matrix for the filter bed. Since I do not use a filter bed the husk can be separated from the proteinaceous material.

The important difference between my method and those heretofore used is that heretofore the sparge water supplied to the mash tun results in supplying to the kettle a series of worts of different specific gravity. Run-off time of the wort from the mash tun heretofore takes from four to five hours. The first wort may be of a specific gravity from 19 to 24 Balling. Each such successive wort fed to the kettle from the tun is of less specific gravity and this change in specific gravity occurring over this long period of time results in less satisfactory color and flavor characteristics.

On the other hand, by my method the mash tun is rapidly discharged to the centrifuges and the various centrifuges each supply extract to the kettle at substantially the same time.

I claim:

1. The method of producing malt extract which consists in grinding the malt and the adjuncts to such a fineness that ninety percent will pass through a hundred mesh screen, forming a thin slurry-like mash of the ground malt and adjuncts in the proportions of approximately two and one-half to three parts by weight of water to one part grain, heating the mash until starch conversion is complete, then without further treatment centrifuging the mash to separate out the fibrous solids, centrifuging the resultant effluent to separate the wort and the non-soluble proteinaceous material, mixing the fibrous and the proteinaceous material with water and subjecting the resultant liquid to a further centrifuging to separate out the fibrous solids, subjecting the resultant effluent to centrifugal separation to separate the wort from the non-soluble proteinaceous material and discharging the fibrous material and the proteinaceous material separately for further treatment.

2. The method of producing malt extract which consists in grinding the malt and the adjuncts separately to such a fineness that ninety percent will pass through a hundred mesh screen, then wetting the malt to form a thin slurry-type mash in the order of two and one-half to three parts by weight of water to one part by weight of dry solids, as is basis, at room temperature, then heating the slurry to approximately one hundred degrees F. and maintaining such temperature for approximately one half hour, meanwhile mixing the adjuncts with from five to ten percent malt in the same general proportion with water and cooking this slurry at a temperature finally reaching but not over two hundred twelve degrees F., then suddenly mixing the adjunct slurry with the malt slurry

whereby the temperature of the mixture is in the neighborhood of one hundred fifty-four degrees F. and maintaining such temperature for approximately twenty minutes until conversion is completed, no starch is left and

5 there is nothing in the mash of higher molecular weight than malto dextrine, then discharging the mash from the conversion zone and clarifying it by centrifugal force to separate the fibrous non-soluble material from the liquor, then subjecting the liquor to centrifugal separation to separate the heavy insoluble proteinaceous material from the wort.

3. The method of producing malt extract which consists in grinding the malt and the adjuncts separately to such a fineness that ninety percent will pass through a

15 hundred mesh screen, then wetting the malt to form a thin slurry-type mash in the order of two and one-half to three parts by weight of water to one part by weight of dry solids, as is basis, at room temperature, then heating the slurry to approximately one hundred degrees F. and main-

20 taining such temperature for approximately one half hour, meanwhile mixing the adjuncts with from five to ten percent malt in the same general proportion with water and cooking this slurry at a temperature finally reaching but not over two hundred twelve degrees F., then suddenly

25 mixing the adjunct slurry with the malt slurry whereby the temperature of the mixture is in the neighborhood of one hundred fifty-four degrees F. and maintaining such temperature for approximately twenty minutes until conversion is completed, no starch is left and there is nothing

30 in the mash of higher molecular weight than malto dextrine, then discharging the mash from the conversion zone and clarifying it by centrifugal force to separate the fibrous non-soluble material from the liquor, then subjecting the liquor to centrifugal separation to separate

35 the heavy insoluble proteinaceous material from the wort, mixing the fibrous material and the proteinaceous material with water, subjecting the resultant liquor again to centrifugal separation whereby the fibrous material and the liquor are separated, then subjecting the liquor again

40 to centrifugal separation to separate the wort from the heavy insoluble proteinaceous material, discharging the wort and the proteinaceous material and the fibrous material for further treatment.

4. The method of preparing malt extract which consists in grinding the malt and the adjuncts to such fineness that ninety percent will pass through a hundred mesh

45 screen, separately cooking the adjuncts with water at a temperature of not to exceed 212° F., meanwhile raising the temperature of the malt with water to a temperature of in the order of 100° F., then mixing the adjuncts and the malt and maintaining them in a conversion zone until conversion is substantially completed, then subjecting without further treatment the entire contents of the conversion zone to centrifugal separation to separate the heavy fibrous solids from the lighter liquids and non-fibrous solids.

5. The method of preparing malt extract which consists in grinding the malt and the adjuncts to such fineness that ninety percent will pass through a hundred mesh

60 screen, separately cooking the adjuncts with water at a temperature of not to exceed 212° F., meanwhile raising the temperature of the malt with water to a temperature of in the order of 100° F., then mixing the adjuncts and the malt and maintaining them in a conversion zone until

65 conversion is substantially completed, then subjecting without further treatment the entire contents of the conversion zone to centrifugal separation to separate the heavy fibrous solids from the lighter liquids and non-fibrous solids, then subjecting the lighter liquid and non-fibrous solids to further centrifugal separation to separate the insoluble proteinaceous material from the wort.

6. The method of preparing malt extract which consists in grinding the malt and the adjuncts to such fineness that ninety percent will pass through a hundred mesh screen, separately cooking the adjuncts with water

at a temperature of not to exceed 212° F., meanwhile raising the temperature of the malt with water to a temperature of in the order of 100° F., then mixing the adjuncts and the malt and maintaining them in a conversion zone until conversion is substantially completed, then subjecting without further treatment the entire contents of the conversion zone to centrifugal separation to separate the heavy fibrous solids from the lighter liquids and non-fibrous solids, then subjecting the lighter liquid and non-fibrous solids to further centrifugal separation to separate the insoluble proteinaceous material from the wort, discharging the wort for further treatment, mixing the proteinaceous material with the fibrous solids in the presence of water and without further treatment subjecting the resultant liquor to centrifugal separation, discharging the heavy non-soluble fibrous material for further treatment.

7. The method of preparing malt extract which consists in grinding the malt and the adjuncts to such fineness that ninety percent will pass through a hundred mesh screen, separately cooking the adjuncts with water at a temperature of not to exceed 212° F., meanwhile raising the temperature of the malt with water to a temperature of in the order of 100° F., then mixing the adjuncts and the malt and maintaining them in a conversion zone until conversion is substantially completed, then subjecting without further treatment the entire contents of the conversion zone to centrifugal separation to separate the heavy fibrous solids from the lighter liquids and non-fibrous solids, then subjecting the lighter liquid and non-fibrous solids to further centrifugal separation to separate the insoluble proteinaceous material from the wort, discharging the wort for further treatment, mixing the proteinaceous material with the fibrous solids in the presence of water and without further treatment subjecting the resultant liquor to centrifugal separation, discharging the heavy non-soluble fibrous material for further treatment, subjecting the lighter effluent to a further centrifugal separation, recovering the heavy non-soluble proteinaceous material for further treatment and discharging the wort for mixture with the wort from the second centrifugal treatment for discharge to kettle and the like.

8. The process of preparing a cereal extract which includes grinding the cereal, mashing the cereal, centrifuging the mash, passing the solids from the centrifuging zone to a sparging zone, withdrawing the centrifuged liquid and re-centrifuging it, returning the sludge from the second centrifuging zone to the sparging zone, removing the clarified liquid which is passed through the second centrifuging zone for use, withdrawing sparged solids from the sparging zone, centrifuging the sparged solids in a third centrifuging zone, removing the centrifuged liquid and re-centrifuging it in a fourth centrifuging zone, withdrawing the finally centrifuged liquid for use, and withdrawing the extracted solids from the last two centrifuging zones for further treatment or use.

9. The process of preparing a cereal extract which comprises grinding the cereal to such a fineness that 80 to 90 per cent will pass through a 100 mesh screen, mashing the cereal, subjecting the mash to a two-stage centrifugal separation, collecting and sparging the solids from both of said stages and subjecting the sparged solids to a two-stage centrifugal separation, and collecting and commingling the effluent from the second stage of both of said centrifugal separations, the first of said two stages separating the fibrous solids from the liquid in each instance, and the second of said two stages separating the non-fibrous solids from the liquid in each instance, the effluent from the first stage constituting the influent of the second stage.

10. The process of preparing a cereal extract which comprises grinding the cereal to such a fineness that 80 to 90 per cent will pass through a 100 mesh screen, mashing the cereal, subjecting the mash to a two-stage centrifugal separation, collecting and sparging the solids

from both of said stages and subjecting the sparged solids to a two-stage centrifugal separation, the first of said stages separating the fibrous solids from the liquid in each instance, and the second of said stages separating the non-fibrous solids from the liquid in each instance, the effluent from the first stage constituting the influent of the second stage, collecting and sparging the fibrous solids from the second mentioned first stage, subjecting the sparged solids to a single stage centrifugal separation, and collecting and commingling the effluent from both of said second stages and from said last-mentioned single stage for use.

11. The method of preparing a cereal extract which includes the steps of grinding the cereal to such fineness that substantially 80 to 90 per cent will pass through a 100 mesh screen, mashing the cereal, and subjecting the mash to two separate extracting operations, each of which comprises a two-stage centrifugal separation, the second extracting operation being preceded by a sparging of the solids resulting from the two stages of the first operation, and the effluent from the second stage of both operations being commingled to provide an extract of a concentration less than that of the effluent from the second stage of the first operation and greater than that of the effluent from the second stage of the second operation, the first stage in each instance separating the fibrous solids from the suspension being centrifuged, and the second stage in each instance separating the insoluble proteinaceous material from the suspension being centrifuged.

12. The method of preparing a cereal extract which comprises the steps of grinding the cereal to such fineness that substantially 80 to 90 per cent will pass through a 100 mesh screen, mashing the ground cereal, and subjecting the mash to three separate extracting operations, the first two of which comprises a two-stage centrifugal separation and the third of which operations comprises a single stage centrifugal separation, the solids resulting from both stages of said first extracting operation being sparged to provide the suspension to be subjected to said second extracting operation, and the solids from the first stage of said second operation being sparged to provide the suspension which is subjected to the third extracting operation, the solids resulting from the single stage of said third operation and from the second stage of said second operation being separately collected, and the effluent from the last stage of each operation being commingled.

13. The process of preparing a cereal extract which includes the steps of grinding the cereal to such fineness that substantially 80 to 90 per cent will pass through a 100 mesh screen, mashing the cereal to provide a mash suspension of fibrous solids and proteinaceous solids, subjecting the mash to a first centrifuging operation to separate the fibrous solids from the suspension, sparging the fibrous solids resulting from the first centrifuging operation and subjecting the sparged solids to a second centrifuging operation, sparging the solids resulting from said second centrifuging operation and subjecting the same to a third centrifuging operation, the effluent from said first centrifuging operation being subjected to a second stage of centrifuging separation to separate said proteinaceous solids from the suspension, and withdrawing the effluent from the said second stage of said first centrifuging operation and from said second and third centrifuging operations for use, the fibrous solids, in each instance, being subjected to continuous separation while in the form of a fluid suspension, and all of said centrifuging operations being carried on continuously and simultaneously.
